UNITED STATES PATENT OFFICE

146,589

DESIGN FOR A PLATE OR SIMILAR ARTICLE

Richard V. Shanklin, Jr., Huntington, W. Va.
Application March 25, 1946, Serial No. 127,939

Term of patent 3½ years

(CL. D44—15)

To all whom it may concern:

Be it known that I, Richard V. Shanklin, Jr., a citizen of the United States, residing at Huntington, in the county of Cabell and State of West Virginia, have invented a new, original, and ornamental Design for a Plate or Similar Article, of which the following is a specification, reference being had to the accompanying drawing, forming part thereof.

Figure 1 is a top plan view of a plate or similar article, showing my new design, and

I claim:

The ornamental design for a plate or similar article, as shown.

RICHARD V. SHANKLIN, JR.
